(57) **CLAIM**

The ornamental design for a rolled product container, as shown and described.

DESCRIPTION

This application is related to U.S. application Ser. No. 29/676,078, filed Jan. 8, 2019, entitled Rolled Product Container, and issued as D858,276, on Sep. 3, 2019, which is a continuation of U.S. application Ser. No. 29/601,826, filed Apr. 26, 2017, entitled Rolled Product Container, and issued as D880,292, on Apr. 7, 2020. The above applications are hereby incorporated by reference as if fully set forth herein in their entirety.

FIG. 1 is a top perspective view of a rolled product container in a closed condition in accordance with the present disclosure.

FIG. 2 is a bottom perspective view thereof.

FIG. 3 is a first side view thereof.

FIG. 4 is a second side view thereof.

FIG. 5 is a third side view thereof.

FIG. 6 is a fourth side view thereof.

FIG. 7 is a top view thereof.

FIG. 8 is a bottom view thereof.

FIG. 9 is a top perspective view of a rolled product container in a closed condition in accordance with a second embodiment of the present disclosure.

FIG. 10 is a bottom perspective view thereof.

FIG. 11 is a first side view thereof.

FIG. 12 is a second side view thereof.

FIG. 13 is a third side view thereof.

FIG. 14 is a fourth side view thereof.

FIG. 15 is a top view thereof; and,

FIG. 16 is a bottom view thereof.

1 Claim, 8 Drawing Sheets
